UNITED STATES PATENT OFFICE.

MARCUS LOEWENTHAL, OF NEW YORK, N. Y.

COMBINED JACKET AND WAIST.

SPECIFICATION forming part of Letters Patent No. 533,994, dated February 12, 1895.

Application filed March 29, 1893. Serial No. 468,235. (No model.)

To all whom it may concern:

Be it known that I, MARCUS LOEWENTHAL, of the city, county, and State of New York, have invented a new and useful Improvement 5 in Blouses or Waists, of which the following is a specification.

My improvement relates particularly to garments intended for children's wear.

The object of my improvement is to provide 10 a garment which will have the appearance of a coat or jacket and shirt waist.

I will describe the garments embodying my improvement, and then point out the novel features in the claims.

15 In the accompanying drawings Figure 1 is a front view of a jacket constructed to have the appearance, not only of an ordinary jacket, but also of a shirt blouse or waist worn under a jacket. This view also represents the upper portion of a skirt. Fig. 2 is a view of the 20 inside of the jacket spread out flat.

Similar letters of reference designate corresponding parts in both figures.

A designates a jacket of ordinary, or other 25 suitable construction.

B designates the upper portion of a skirt, or it may be regarded as representing the upper portion of a pair of pants.

C designates an appendage of the jacket, 30 and this is made to represent a shirt waist or analogous article. This appendage consists of that portion of a shirt waist or analogous article which would ordinarily appear or be exposed to view when a jacket is worn over 35 such an article, and comprises means for fastening it to the jacket. To explain more in detail, the appendage C consists of a skirt portion c, which as shown is provided at the upper edge with buttonholes, c', for engaging 40 with buttons a, fastened to the inside or lining of the jacket A, two facing portions c², c³, extending upwardly from the skirt portion c, and provided with buttonholes c⁸ for engaging 45 with buttons a', secured to the inside or lining of the jacket A, and a neckband or cross-band c⁴, provided with one or more buttonholes, c⁵, for engaging with one or more buttons secured to the inside or lining of the jacket A. The facing portions, c², c³, are constructed to be united; one being provided 50 with buttons c⁷, and the other with buttonholes c⁸. The neckband or crossband is pro-

vided with a collar c⁹, which may be folded over the top edge of the jacket A.

The jacket A may have a collar of its own, so that it could be worn without the collar c⁹.

Of course, I do not wish to be confined to buttons and buttonholes as a means for fastening the parts together or for uniting the facing portions, c², c³.

What I claim as my invention, and desire to secure by Letters Patent, is—

1. The combination of a jacket or analogous article whose adjacent front edges are separated from each other, a shirt waist or blouse consisting of a body portion extending below the lower edge of said jacket and a facing portion which is exposed through the opening between the front edges of the jacket, and means for detachably securing the facing portion to such front edges, and the body portion to the lower edges of the jacket, substantially as specified.

2. The combination of a jacket or analogous article whose adjacent front edges are separated from each other, a shirt waist or blouse consisting of a body portion extending below the lower edge of said jacket and a facing portion which is exposed through the opening between the front edges of the jacket, said facing portion being provided with an opening, and means for detachably securing the edges of the opening in said facing portion, the facing portion to the front edges of the jacket, and the body portion to the lower edges of the jacket, substantially as specified.

3. The combination of a jacket or analogous article, a shirt waist or blouse consisting of a body portion extending below the lower edge of said jacket and a facing portion which extends upward opposite the front portion of the jacket, and means for detachably securing the facing portion to the front of the jacket and the body portion to the lower edges of the jacket, substantially as specified.

In testimony whereof I have signed my name to this specification in the presence of two subscribing witnesses.

MARCUS LOEWENTHAL.
